UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

CASING FOR LAMP-SOCKETS OR THE LIKE.

1,228,027.

Specification of Letters Patent. Patented May 29, 1917.

Application filed December 8, 1913. Serial No. 805,290.

To all whom it may concern:

Be it known that I, CHARLES J. KLEIN, a citizen of the United States, residing at Milwaukee, in the county of Milwaukee and 5 State of Wisconsin, have invented new and useful Improvements in Casings for Lamp-Sockets or the like, of which the following is a full, clear, concise, and exact description, reference being had to the accompanying drawing, forming a part of this specification.

This invention relates to casings for lamp sockets, pendent switches and the like.

One of the objects of the invention is to 15 provide improved interlocking means for the sections of such casings which may be released by compression of the outer section to expand the same at the points of interlock.

20 In order that my invention may be more clearly understood I have illustrated certain embodiments thereof in the accompanying drawings. The forms shown, however, have been chosen as exemplary of my invention 25 and may be modified in certain respects without departure from the scope of the appended claims.

Figure 1 is a perspective view of a lamp socket casing showing the parts separated; 30 Fig. 2 is a similar view of a modified form of casing; and,

Figs. 3, 4, 5, and 6 are perspective views of additional modifications of the casing, the shell in each case being partially broken 35 away.

Each of the casings illustrated comprises a cap 1 and a resilient shell 2 designed to house a switch mechanism or other device. Interlocking means are provided on the 40 overlapping margins of the sections for releasably securing the same together. In the preferred form this interlocking means comprises catches 3 on one section and co-operating shoulders 4 on the other. In practice, 45 two sets of interlocking means are employed at diametrically opposite points of the casing in such a manner that the sections may be released for separation by compression of the outer member, that is the shell, to expand the same at the points of interlock.

Referring now to Fig. 1, the cap 1 is provided with a bead 5 which merges at the transverse ledge 6 into a circular depending rim 7. The shoulders 4 are provided in the 55 rim 7 and preferably immediately adjacent

the ledge 6. While the shoulders 4 are shown as comprising apertures, it is to be understood that the same may be formed in various ways.

The shell 2 is designed to fit over the cap 60 rim 7 and is of an end diameter approximately equal to the diameter of the cap through the bead 5. The catches 3 are provided on opposite sides of the shell margin and limited portions 8 of the latter 65 about the catches are indented. The interior diameter of the shell between the indented portions is substantially equal to the exterior diameter of the cap through the rim 7 so that the sections are held concentrically 70 when attached and a slight radial clearance is provided between the edge of the shell, other than the portions 8, and the cap rim. This clearance is provided for a purpose hereinafter set forth and is preferably at 75 least equal to the radial length of the catches 3. These catches may be of any suitable form, those illustrated being of the type described and claimed in my co-pending application, filed Oct. 28, 1913, 80 Serial No. 797,871. In this form, each catch comprises a substantially triangular portion of the shell wall at its edge crimped inwardly to form a bearing surface and reinforcing side walls, the latter being inherently beveled toward the cap. Slots 9 to receive the switch operating member may be 85 provided in opposite sides of the shell margin and at right angles to the catches 3. If desired, the edge of the shell may be turned slightly, as at 10.

The cap and shell may be telescoped together in the conventional manner, the shell, however, encircles the cap rim 7, as described. In assembly, the interlocking 95 means are first aligned and the sections of the casing then pushed together. During the latter operation the shell assumes an elliptical shape until the catches 3 slip over the cap rim 7 and register with the apertures 4, whereupon the shell resumes its cylindrical form as the catches snap into the apertures. The bearing surfaces of the catches thereupon coat with the shoulders 4 to lock the sections against both axial separation and relative rotation. The shell margin at the same time abuts the ledge 6 of the cap to prevent relative rocking of the parts.

Separation of the cap and shell may be 110

readily accomplished by compression of the outer member, that is the shell, at right angles to the interlocking means. As above described, the radial clearance between the 5 cap rim 7 and the shell margin is sufficient so that the shell under such compression may again assume its elliptical shape until the catches 3 are withdrawn from the shoulders 4, whereupon the shell may be pulled away 10 from the cap.

The interlocking means of the casing illustrated in Fig. 2 is similar in many respects to the form already described. In this embodiment, however, the cap rim is 15 provided on opposite sides with distended portions 11 in which the shoulders 4 are located. The margin of the shell is circular and of a diameter approximately equal to the exterior diameter of the cap through the 20 portions 11. The catches 3 are provided on the shell, and are similar to those previously described. The method of uniting and separating the sections of the casing when thus formed is the same as that described in connection with the casing shown in Fig. 1.

Figs. 3, 4, 5, and 6 illustrate casings having overlapping portions and abutting edges. As in the casings of Figs. 1 and 2, interlocking means for the sections are provided on 30 the overlapping portions thereof.

The cap 1 of Fig. 3 is provided with a transverse marginal flange 12 and oppositely disposed depending tongues 13. The catches 3 in this embodiment are carried by the 35 tongues 13 while the shoulders 4 are provided in opposite sides of the cylindrical shell 2. Assembly of the sections is accomplished by telescoping the parts together, while separation thereof is readily effectible 40 by compression of the shell to expand the same at the interlocking points. The in-turned edge 10 of the shell is especially advantageous in this embodiment (and certain of the others) inasmuch as pockets 14 are 45 thus provided to receive the tongues 13.

Fig. 4 shows a casing for keyless sockets in which the margin of the shell is unbroken. In this embodiment the sections are substantially similar to the casing shown in 50 Fig. 3, except that the shoulders 4 are provided in the depending tongues 13 and the catches 3 are located on corresponding portions of the shell margin. Assembly and separation of the sections is accomplished in 55 the manner set forth in connection with the casing of Fig. 3.

The depending tongue 13 of the cap shown in Fig. 5 is substantially semi-circular and provided with two of the catches 3 on its 60 curved edges, disposed at opposite angles of approximately 45° to the cap flange 12. The shell 2 designed for use with this cap is provided with two pairs of the shoulders 4 on opposite sides and also inclined at 65 opposite angles of approximately 45° to the

shell margin. Attachment and separation of the parts remains similar to that already described. The two pairs of interlocking means in this embodiment materially increases the effectiveness of the interlock between the two sections without increasing the manufacturing cost.

In the form shown in Fig. 6 two substantially rectangular tongues 13 are provided on opposite sides of the cap and a pair of 70 shoulders 4 provided in the tongue at opposite angles of approximately 45° to the cap rim. The shell in this embodiment carries a pair of the catches 3 at the corners of the oppositely disposed key-slots 9, so that the 75 interlocking means for the sections are provided adjacent the operating member of the switch. Accessibility of the shell to compress the same to release the interlock is thus 80 facilitated.

Guide notches 15 may be provided in the edge of each section carrying the shoulders 4 to facilitate assembly of the parts.

What I claim as new and desire to secure by Letters Patent is:

1. A casing for lamp sockets comprising separable sections having overlapping portions provided with interlocking means engageable by contraction of one of said sections about the other and releasable by contraction of one of said sections at a point remote from said means with a resulting expansion of said section adjacent said means.

2. A casing for lamp sockets comprising separable sections having interlocking means therefor, one of said sections being relatively rigid, the other said section being resilient and contractible, independently of said first mentioned section, at a point remote from said interlocking means, with a resultant expansion adjacent to said means, and said means being releasable by such expansion of said resilient section.

3. A casing for lamp sockets comprising a cap and shell of unequal diameters, and cooperating shoulders carried thereby for locking said parts together, said parts having radial clearance at a point removed from said shoulders whereby the latter may be released by compression of said part of greater diameter at said point of radial clearance.

4. A casing for lamp sockets comprising sections having interfitting marginal portions, and interlocking means for the sections comprising a catch on one and a shoulder on the other, the outer section being resilient and having radial play with respect to the inner section at substantially right angles to the interlocking means whereby said section may be compressed at substantially right angles to said means to expand the same at said means.

5. A casing for lamp sockets comprising a cap and shell having interfitting marginal

portions, certain portions of said shell being held against radial compression by portions of said cap received therein, and other portions of said shell being radially compressible to expand said first-mentioned portions, and interlocking means carried by said incompressible portions of said shell and the portions of said cap received therein.

6. A casing for lamp sockets comprising 10 separable sections having wall portions to overlap and edge portions to abut each other and interlocking means for said sections releasable by contraction of one said section at right angles to said means.

Copies of this patent may be obtained for five cents each, by addressing the "Commissioner of Patents, Washington, D. C."

7. In combination, a cap having a depending tongue, a resilient shell adapted to overlap said tongue, and coöperating shoulders on said tongue and said shell for locking said cap and shell together, said shell being inwardly yieldable at points removed from 20 said shoulders to release the latter.

In witness whereof, I have hereunto subscribed my name in the presence of two witnesses.

CHARLES J. KLEIN.
